UNITED STATES PATENT OFFICE.

CHARLES T. WOOTTEN, OF PHILADELPHIA, PENNSYLVANIA. ASSIGNOR TO TOLBERT N. RICHARDSON, OF PHILADELPHIA, PENNSYLVANIA.

CAN LID OR TOP.

1,151,322.

Specification of Letters Patent. Patented Aug. 24, 1915.

Application filed June 13, 1914. Serial No. 844,987.

To all whom it may concern:

Be it known that I, CHARLES T. WOOTTEN, a citizen of the United States, residing in the city and county of Philadelphia, State 5 of Pennsylvania, have invented a new and useful Can Lid or Top, of which the following is a specification.

My invention consists in making the lid or top of a can partly transparent, whereby 10 the contents of the can may be viewed or shown and inspected from the exterior, said lid being adapted to hold a piece of glass or other transparent material employed in a firm and convenient novel manner without 15 soldering or attached fastening members.

The invention is satisfactorily illustrated in the accompanying drawing, but the important instrumentalities thereof may be varied, and so it is to be understood that 20 the invention is not limited to the specific details shown and described.

Figure 1 represents a perspective view of a can-lid embodying my invention. Fig. 2 represents a diametrical section thereof on 25 the line $x-x$ Fig. 1. Fig. 3 represents what may be termed a blank from which the lid and its novel features are produced.

Similar numerals of reference indicate corresponding parts in the figures.

Referring to the drawings, 1 designates 30 the lid of a can, the same being open at the top and having on the circumferential wall of said opening the inturned rim 2 which is joined by a bend on the exterior thereof 35 with the inturned rim 3, said rims being separated forming between them the channel 4 in which is received the peripheral portion of the piece 5 of glass which closes the open top of the lid from below, said 40 rims being swaged or compressed against the upper and lower faces of said portions of the piece 5, they firmly holding the latter in position.

In the manufacture of the article, I employ 45 the shape shown in Fig. 2, the same consisting of an annular piece of metal having its center cut-out forming the open top of the lid, the flange or wall 6 of said opening, the vertical side 7 extending downwardly from said flange, the top inclined wall or plate member 8 bent outwardly from

said side, and the circumferential exterior rim 9 around said wall 8, said rim 9 being the vertically extending side rim of the lid.

The side 7 is swaged outwardly forming 55 the rims 2 and 3 with the channel 4 within the same in which latter the periphery of the piece 5 of glass is seated, the inturned rim 3 having its inner terminal joining the inner terminal of said wall 8 by the crimp 10, 60 the rim 3 thus joining the upper member of said crimp and being seated on the lower member of said crimp whereby it is firmly sustained in position and with it a piece of glass or other transparent material, it being 65 seen that there is an opening in the top, the crimp 10 forming the lower wall thereof, and the edges 2 of the channel 4 forming the upper wall thereof, and as the piece of glass which closes said opening is held by its peripheral portion in said channel it rests on the lower wall 8 by the crimp 10 on the annular part 6, said part and crimp forming 70 a strong support for said peripheral portion so that the piece of glass is not liable to rattle, break-down or sag, it being noticed also that the periphery of the piece 5 is covered by the rims 2 and 3, and the exterior bend of the latter, so as not to be exposed. Furthermore, the crimp 10 forms a stiff connection 75 for the lower rim 3 with the wall 8, and as said lower rim joins the upper member of said crimp 10 and is seated on the lower member thereof as has been stated, the rims 2 and 3 which form said channel are firmly 80 supported from below on said crimp and thus on the wall 8, which is inturned from the side rim 9 of the lid whereby said rims are not liable to yield and break downwardly, and thus the piece of glass, whose 85 periphery occupies said channel and its adjacent portion is sustained on the lower rim 3 and consequently the crimp 10, so that it is not liable to be fractured, as the latter forms a rigid seat for the rims 2 and 3, and 90 consequently for the peripheral portion of said piece of glass received therein.

Having thus described my invention what I claim as new and desire to secure by Letters Patent, is:—

A can top having therein an opening, a rim on its periphery, a plate-member ex-

tending inwardly from said rim, a crimp on the inner periphery of said plate member forming the lower wall of said opening, a rim rising from said crimp having therein 5 an inwardly facing channel, the upper edge of said channeled rim forming the top wall of said opening, and a piece of transparent

material having its peripheral portion occupying said channel, resting on said crimp and closing said opening.

CHARLES T. WOOTTON.
